[22] Filed: Dec. 26, 1995

CLAIM

[51] LOC (6) Cl. 21-02

The ornamental design for a bumper for a skate boot, as shown.

[52] U.S. Cl. D21/225; D21/226; D21/230;

DESCRIPTION

D2/904

[58] Field of Search D21/224-230;
D2/904, 318; 280/11.18, 11.19, 11.2, 11.22,
11.27, 8.11; 36/115, 28, 69, 71FIG. 1 is a front elevational view of a skate showing a new ornamental design for the bumper for a skate boot;
FIG. 2 is a back elevational view thereof;
FIG. 3 is a top plan view thereof;
FIG. 4 is a bottom plan view thereof;
FIG. 5 is a left side elevational view thereof; and,
FIG. 6 is a right side elevational view thereof.
The broken line showing of the skate in FIGS. 1-6 is for illustrative purposes only and forms no part of the claimed design.
